US0D1076627S

(12) **United States Design Patent** (10) **Patent No.:** **US D1,076,627 S**
(45) **Date of Patent:** **** May 27, 2025**

(54) **SOCKET WRENCH TOOL**

(71) Applicant: **Jianxia Gao**, Anqiu (CN)

(72) Inventor: **Jianxia Gao**, Anqiu (CN)

(**) Term: **15 Years**

(21) Appl. No.: **29/989,192**

(22) Filed: **Feb. 11, 2025**

(51) LOC (15) Cl. **08-05**

(52) U.S. Cl.

USPC **D8/70**

(58) **Field of Classification Search**

USPC D8/70, 29, 86, 14
CPC .. B25B 23/0035; B25B 13/5091; B25B 13/48

See application file for complete search history.

(57) **CLAIM**

The ornamental design for a socket wrench tool, as shown and described.

DESCRIPTION

FIG. 1 is a front perspective view of a socket wrench tool, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view.

1 Claim, 8 Drawing Sheets
